COMPUTING MACHINE

Filed Jan. 21, 1927

UNITED STATES PATENT OFFICE

FREDERICK A. HART, OF NEW BRITAIN, CONNECTICUT, ASSIGNOR TO REMINGTON TYPE-WRITER COMPANY, OF ILION, NEW YORK, A CORPORATION OF NEW YORK

COMPUTING MACHINE

Application filed January 21, 1927. Serial No. 162,473.

My invention relates to computing machines. In these machines there are parts of the mechanism that are required to move with a considerable degree of precision and at the same time, especially in computing machines of that class in which the computing mechanism is operated by the keys of a typewriter, it is necessary that the parts move freely so as to offer as little resistance as possible to the operation of the key. The present invention has for its principal object to improve mechanism of this character in respect to precision of movement and readiness, accuracy and permanency of adjustment, together with freedom of movement; and to attain these objects with mechanism that may be easily and cheaply manufactured.

To the above and other ends my invention consists in certain features of construction and combinations and arrangements of parts, all of which will be fully described herein and particularly pointed out in the claims.

I have shown my invention applied to a Remington combined typewriting and computing machine, the general construction and mode of operation of which are well-known in the art. For the purposes of the present invention the machine may, if desired, be made as described in the patent to Wahl No. 1,270,471, dated June 25, 1918, except as hereinafter pointed out. In other words, for the purpose of description the invention in the form in which it is set forth herein may be regarded as an improvement in the mechanical structure of the machine described in said patent. In view of what has just been said, the accompanying drawing shows only so much of the machine as is necessary to illustrate my improvements.

In said drawing, which is more or less fragmentary,

Figure 1 is a front view;

Figure 2, a right-hand view in section on the line 2—2 of Figure 1;

Figure 3 is a section about on the line 3—3 of Figure 1 and looking toward the left.

Figure 4 is a perspective of one of the differential arms and associated parts disassembled.

Figures 3 and 4 are on a larger scale than Figures 1 and 2.

The Remington combined typewriting and computing machine comprises a Remington typewriter having attached thereto computing mechanism of the sort described in the Wahl patent above referred to. The actuator of said computing mechanism comprises a main frame casting 10 secured to the top plate of the typewriter and a number of sheet metal frame plates projecting in front and rear planes from said casting.

Seven of said plates are shown in the drawing and designated 11, 12, 13, 14, 15, 16 and 17. Plates 11 and 14 may be regarded as the two end plates of the vertical actuator and these are secured respectively to two forwardly projecting lugs or brackets 18 and 20 integral with main casting 10. Plate 15 is the left-hand end plate of the cross actuator, the right-hand end plate of which is not shown, but in the machine it is supported on the extreme right-hand end of the casting 10. The frame plates 15, 16 and 17 are supported directly or indirectly from plate 14 and the right-hand end plate, not shown, the supports consisting of certain cross rods or posts, some of which are shown and lettered 21, 22, 23 and 24. Each of the parts marked 21, 22 and 23 consists of a rod running through all of the plates and having sleeves or bushings strung on it to space the plates apart. The bracket or plate 11 is fastened to the main casting by two screws 25 and plate 14 by two screws 26.

Each of the ten numeral keys of the typewriter has connected thereto a link 27, Fig. 3, which at its upper end is pivoted to a so-called "fan" 28, the hub of which is journaled on a cross rod 30 of the vertical actuator. The fan 28 has an opening 36 through which a stud 37 projects from a goose-neck cam 38 which is pivoted on the rod 30. This goose-neck cam has at its outer end a concentric slot 41 adapted to co-operate with a cross or wrist pin 42 in an arm 43 secured to and projecting from a differential rock shaft 44, which is journaled in the frame plates 11 and 14 and which is also supported near its middle where it passes through the 100

plate 13 by three ball-bearing rollers 91, 92 and 93 (Figs. 1 and 3). This differential rock shaft 44 carries the usual peculiar hub structure 45 to which at 46 is pivoted the usual gear sector or segment 47 which operates the vertical master wheel. This gear segment is arranged to act on the down stroke of the key on a drive pinion 48 for addition or on an auxiliary pinion 50 for subtraction, said pinions being in mesh with each other and the former splined on the shaft 51 of the vertical master wheel 52 which drives the so-called carrying wheels 53 of the vertical totalizers, the last traveling back and forth in unison with the typewriter carriage; all of these parts being and operating the same as heretofore.

Journalized in the frame plates 15 and 16 is the differential shaft 54 of the cross footer on which the gear sector or segment 55 is mounted after the same fashion as the vertical gear sector 47. The sector 55 is adapted to mesh for addition with the drive pinion 56 and for subtraction with another drive pinion not shown, the pinion 56 being splined on the shaft 57 of the cross master wheel 58, said shaft journalized in the frame plates 15 and 17, all as heretofore. The two differential shafts are driven in unison by a linkage situated between the plates 14 and 15 and comprising an arm 60 fast on the right-hand end of shaft 44, an arm 61 fast on the left-hand end of shaft 54 and a connecting link 62.

All the parts above referred to perform substantially the same functions as heretofore.

The differential shaft 44 has heretofore had a plain bearing in each of the frame plates 11 and 14 and has been supported at the frame plate 13 by having mounted thereon a plain bearing sleeve. It is necessary that this shaft move with considerable precision because its function is to turn the master wheels 52 and 58 as exactly as possible a definite number of tooth-spaces, depending in each instance on the value of the numeral key operated. It is necessary at the same time that this shaft turn quite freely because it is operated rapidly by the down stroke of a typewriter key. I have therefore mounted this shaft on ball bearings by means described and claimed in an application which is a division of this one.

The shaft 44 is of some length and some of the differential arms 43 are mounted near the middle of it, and the segment 47 is also mounted at some distance from the end of it. As it is these differential arms and this segment 60 that are required to move with precision it is essential that the shaft do as little springing as possible under the force of the key operation. It is for this reason that in the machine as heretofore constructed a bearing sleeve has been provided at the frame plate

13, and I also support the shaft at that point but by the rollers 91, 92, 93 above mentioned. This shaft turns through an angle of about forty degrees, and in that angle it can be sprung a little if it was not absolutely straight in the first instance without imposing noticeable resistance on the key stroke, provided the bearing at the middle and those at the ends are sufficiently near frictionless. To this end I guide the shaft at the frame plate 13 by means of three ball bearing rollers 91, 92 and 93, these rollers being situated of course at about one hundred and twenty degrees from each other around the shaft. In order to accommodate this guiding system the plate 13 has been cut away so as not to touch the shaft.

The differentially or spirally disposed rock arms 43 shown in the drawing replace arms heretofore used in exactly the same situation and arrangement. Heretofore, each goose-neck 38 has come down between two arms, each having its own hub separately mounted on the shaft 44 and secured thereto by a pin driven through the hub and shaft. A roller having trunnions at its ends was journalized between these two adjacent arms and cooperated with the cam slot 41 in the goose-neck. It is, of course, essential that these arms be disposed with accuracy because the extent to which each key will turn the differential shaft depends entirely on the angle at which the arm projects from the shaft. These arms have heretofore been mounted on the shaft by the aid of an expensive jig which located all of the arms as exactly as possible in their correct relationship to the segment 47, the holes being drilled and the pins driven while the parts were in the jig. After removal from the jig it would sometimes be found that the arms were not in exact position and sometimes that the driving of the pins had bent or distorted the shaft. The shaft would then be straightened and the arms adjusted by bending and peening. This shaft with its fixtures thereon was therefore quite an expensive affair.

In order to improve the situation above described I make each arm 43 or pair of such arms as an integral piece of steel having a split hub secured on the shaft by a clamp screw 137. In Fig. 4 and in other figures I have shown these hubs cut away as much as possible as for example at 138 and 140, this being for the sake of lightness made desirable by the number of these arms that are mounted on the shaft and the rapidity with which the shaft has to be operated by a light stroke on the typewriter key. The pair of arms desired is secured by cutting in the piece a slot in a plane perpendicular to the shaft as shown for example in Fig. 4. With a piece made this way it is not practicable to mount between the two arms a roller having trunnions as heretofore practised. I accordingly drill

a hole 141 through the two arms and insert therein a bearing piece or wrist 42 consisting of a small tube of steel. This tube or hollow rod is inserted through the hole or holes 141 and a piece of wire 142 is passed through the hollow rod 42 and its ends bent down making ears or tines 143 which overlap the arms 43 in such a manner as to prevent the rod 42 from coming out of the holes. This rod is made very hard and is ground to precision. It does not act as a roller but it is loose enough to creep, as it were, in the holes 141 under the action of the goose-neck 38 so that it does not always present the same part of its surface to said goose-neck. The whole construction is such that the device works smoothly and is sufficiently durable. If at any time one of these bearing pieces 42 should show any appreciable wear it is the work of but a few seconds to replace it with a new one, it being necessary only to straighten out one of the tines 143 sufficiently to allow the withdrawal of the bearing piece 42 and the wire 142 which can be replaced by new parts by merely inserting them and bending the wire.

The shaft 44 has other devices mounted on it, for example an arm 144, Fig. 1, which is used for certain locking purposes and in connection with a disconnect lever, and another arm 145 which has connected with it the returning spring 146 for the shaft and which also cooperates with a certain locking device 147. As heretofore constructed all of these parts have been mounted on the shaft in the jig by pins driven through the hubs of the arms.

With the present construction the devices are not mounted on the shaft in a jig but are adjusted in the machine itself. For example, the extreme left-hand arm 43 cooperates with the "1" numeral key. Segment 47 is set by means of a gage in the position to which this key should move it. The key itself is depressed so as to bring its goose-neck 38 into engagement with the follower 42 and the clamp screw 137 is tightened. The entire adjustment of this arm is then complete taking account as it does of all inaccuracies of manufacture, either in the shaft 44 itself, in the arm 43, or in the goose-neck 38. The whole purpose of this arm and goose-neck is to move the segment 47 one tooth space from normal and if the adjustment is made as described then all of the parts, whatever their initial inaccuracy of manufacture may be, are in the correct relationship to cause the "1" key to do exactly that. The other arms are adjusted in the same way. It will be perceived that by employing the improved arms described, a good deal of time and expense is saved in the manufacture of the machine.

It should also be remarked that this split hub construction takes a very firm hold on the shaft and is a thoroughly reliable con-

struction. It will be observed from the drawing that I have utilized it in other situations in the machine, aside from the arms 43. For example, the shaft 54 has an arm 148 mounted on it by this same construction, this arm being adapted to contact with some stationary part of the machine, in the present instance with the rod 118, to arrest the shaft 54 in its normal position. It will be perceived that once this shaft is set in its normal position by means of a gage applied to the segment 55, it is the work of but a few seconds to turn this arm 148 down against the rod 118 and to tighten its clamp screw 150.

Various changes may be made without departing from my invention.

What I claim as new and desire to secure by Letters Patent, is:

1. In a computing machine, the combination with a rock shaft and a cam for rocking said shaft, of an arm having a split hub and a clamping screw whereby it is secured rigidly to said shaft in adjusted position, said arm being slotted in a plane perpendicular to said shaft so as to make two branches, a hollow pin or follower piece loosely inserted in holes through said branches, and a wire passing through said hollow pin and bent at the ends thereof to prevent said pin from coming out of said holes.

2. In a computing machine, the combination with a rock shaft and a cam for rocking said shaft, of an arm having a split hub and a clamping screw whereby it is secured rigidly to said shaft in adjusted position, said arm being slotted in a plane perpendicular to said shaft so as to make two branches, a hollow pin or follower piece inserted in holes in said branches with enough looseness to enable it to creep under the action of said cam so as at different times to expose different parts of its surface to such action, and means for preventing said pin from coming out of said holes.

3. In a computing machine, the combination with a rock shaft and a series of cams for rocking said shaft differentially, and a cam for each digit, of a series of arms mounted on said shaft, an arm for each of said cams, each of said arms having a split hub and a clamp screw whereby it can be rigidly secured to said shaft in adjusted position, and each said arm being slotted perpendicular to said shaft and having a follower pin inserted in holes in the branches thereof for cooperation with its associated cam.

4. In the differential mechanism of an adding machine, a cam-operated device including a bifurcated arm having holes through the branches of the arm, a tubular follower loose in said holes, and means for preventing the follower from coming out of the holes endwise.

5. In the differential mechanism of an

adding machine, a cam-operated part slotted to form two branches having holes extending through the branches, a tubular follower loose in said holes and a wire extending through the tube and bent at its ends to prevent the follower from coming out of the holes.

Signed at the Borough of Manhattan, city of New York, in the county of New York and State of New York this 20th day of January A. D. 1927.
